CLAIM

The ornamental design for a golf club grip, as shown and described.

DESCRIPTION

FIG. 1 is a top, left isometric environmental view of the golf club grip including a portion of a golf club shaft shown in phantom lines.

FIG. 2 is a left side elevational view of the golf club grip shown in FIG. 1.

FIG. 3 is a rear elevational view of the golf club grip.

FIG. 4 is a right side elevational view of the golf club grip.

FIG. 5 is a top plan view of the golf club grip; and,

FIG. 6 is a bottom plan view of the golf club grip.

The broken line showing of a fragmented shaft is for illustrative purposes only and forms no part of the claimed design.
